UNITED STATES PATENT OFFICE

MICHAEL A. MESSLEIN, OF CHICAGO, ILLINOIS

CONVEYING APPARATUS

Application filed October 10, 1928. Serial No. 311,525.

This invention relates to conveying apparatus, and particularly to apparatus useful in connection with electroplating tin mill black sheets or any other articles.

5 The apparatus of this invention receives in compact pack the sheets to be plated and delivers the same singly to the conveying mechanism which is arranged to automatically pass said sheets successively through 10 the several separate tanks included in the machine for cleaning, washing, plating, oiling and the like and then removing said sheets from the machine.

An object of the invention is to provide 15 an automatic electroplating apparatus.

Another object of the invention is to provide an automatic electroplating apparatus wherein a continuous row of articles, spaced at predetermined intervals, are moved 20 through successive tanks, wherein various operations incidental to electroplating are performed.

A further object of the invention is to provide transfer mechanism for plating machines whereby work is delivered to a tank, moved through the tank, and then removed 25 from said tank automatically.

A still further object of the invention is to provide an electroplating machine, including 30 a plurality of tanks, with mechanism for automatically receiving work pieces to be plated, moving said pieces through a tank, then removing same from said tank and delivering the pieces to another tank and so 35 on until the work pieces have passed through the several tanks of the machine and then delivering said work pieces out of the machine.

A further object of the invention is to provide an electroplating apparatus which is 40 economical to manufacture and efficient in operation.

According to the invention the transfer mechanism comprises an endless chain disposed over a tank, which chain carries a 45 plurality of skeleton box-like frames for receiving single sheets, which sheets are delivered automatically to these frame members and are moved through the tank by the frames and then delivered to the transfer 50 mechanism of a subsequent tank where the

movement of the sheet is repeated. There are as many tanks and transfer mechanisms as the particular plating requires together with such washing, rinsing and oiling tanks as may be found necessary.

55 The form of the machine chosen to illustrate an embodiment of the invention is arranged to plate flat sheets and the views of the accompanying drawings are as follows:

60 Figure 1 is a side elevational view somewhat diagrammatic in form, and illustrated in two parts, of a plating machine consisting of four tanks together with the conveyor mechanism embodying my invention.

65 Figure 2 is a side elevational view of the receiving end of the machine showing details of construction.

70 Figure 3 is a vertical section through the machine showing certain details of construction with certain parts fragmentally disclosed.

75 Figure 4 is a vertical section through the plating tank of the machine.

Figure 5 is a top plan view of the plating section tank showing one form of disposition of the anodes.

80 Figure 6 is a perspective view of one of the anodes.

Figure 7 is a section taken on line VII—VII of Figure 6.

85 Figure 8 is an enlarged fragmental portion, partially in section, of one end of one of the sheet carriers as the same appears in the plating tank section of the machine.

Figure 9 is a perspective view of one of the sheet carriers of the conveyor mechanism.

Figure 10 is a top plan view of a portion of the supply hopper with certain parts in section and with the pack of sheets omitted.

90 Figure 11 is an elevational view partially in section of the trip mechanism for removing a sheet from the frame-like carrier.

95 Figure 12 is a view similar to Figure 11 showing the trip finger as the same appears as a sheet has been removed from a frame carrier with the dislodged sheet shown in dotted lines.

100 Figure 13 is a fragmental side elevational view of the lower end of the supply hopper bottom.

Figure 14 is a section taken on line XIV—XIV of Figure 10.

Figure 15 is a fragmental elevational view of one corner of a frame carrier showing the 5 wheel for supporting said carrier on the bus bar of the plating section.

The framework of the invention illustrated 10 comprises a plurality of structural steel members including uprights 1 and horizontal connecting members 2, connected together to form a frame structure.

A plurality of tanks, A, B, C, and D, are arranged lengthwise of the machine and rest on the floor or foundation of the machine.

15 These tanks are arranged endwise so that work pieces may be advanced successively through the several tanks for carrying out certain functions and steps in the plating operations.

20 The tanks in the illustrated embodiment of the invention may be termed as follows: Tank A is the cleaner tank, tank B the washing water tank, tank C the plating tank, and tank D the oil tank. Of course, as many or 25 as few tanks as desirable may be arranged and grouped into a plating machine as the particular kind of plating requires, both as to the actual plating of the work pieces as well as the preliminary and subsequent washing, 30 rising, and cleaning operations are concerned.

A transfer mechanism is provided for every one of the several tanks, which mechanism is similar in all respects except as to the length of the conveyor chains for the several 35 tanks as some of the tanks are longer than others. The plating tank, for instance, in the illustrated form of the invention is shown as being considerably longer than any of the other tanks. Necessarily the conveyor or 40 transfer mechanism for this tank must be longer than the conveyor or transfer mechanism from the other tanks.

A sheet hopper 3 comprising an inclined floor 4 is supported by the first and second 45 vertical members 1 of the frame structure. Near each side of the floor 4 are side guides 5 and 6 which in the present instance comprise angle bars. A plurality of slides 7 are arranged in the front or lower end of the hopper 3 as shown in Figures 1, 2, 10, 13, and 14 of the drawings. A transverse shaft 8 supported in depending ears 9 underneath the floor 4 of the hopper carries rollers 10 underneath the several slides 7. Springs 11 are 55 interposed between the rear ends of each of the slides 7 which springs rest against abutments 12 for normally urging the slides outwardly of the end of the floor 4. These slides 7 are provided so that when the front sheet of 60 the pack within the hopper 3 is withdrawn as hereinafter explained the slide will move backwardly and thus permit removal of the front sheet from the pack.

Spaced from the front or lower end of the 65 floor 4 of the hopper 3 is an upwardly extend-

ing outwardly inclined wall 13 having vertical slots 14 formed in the same. A slide 15 which comprises a plate having ribs 16 thereon which ribs extend through the slots 14 in the plate 13 is arranged to slide vertically outside of the plate 13. The pusher plate for removing the front sheet of the pack in the hopper 3 consists of a thin bent sheet or plate of metal 17 which is fastened to the ribs 16 of the plate 15 and thereby moves with said plate. The width of the pusher plate 17 is greater than the distance between the side guides 5 and 6 which are attached to the floor 4 of the hopper. It is of course understood that the side guides 5 and 6 are adjustable laterally to accommodate sheets of different sizes.

25 A motor shaft 18 is arranged transversely of the machine near the hopper 3 in suitable bearings. A gear 19 thereon meshes with a larger gear 20 carried by shaft 21 in the machine frame. A small gear 20a on shaft 21 meshes with gear 24 on shaft 23. A small gear 22 on shaft 23, which is also supported in the machine frame, meshes with gear 27 30 on shaft 26, which shaft 26 carries a bevel gear 25 which is in mesh with bevel gear 29 fastened to driving shaft 30, which shaft extends lengthwise of the machine and operates the conveyor mechanism for the several 35 tanks.

An arm 31 is pivoted at 32 to a fitting 33 secured to one of the vertical uprights 2 of the frame structure adjacent the hopper 3. A link 34 is pivoted at 35 to the arm 31 and at the other end said link is pivoted at 36 to spaced ears 37 on the plate 15 which is connected to the pusher plate of the supply hopper.

40 A pitman 38 has one end pivoted at 39 to the arm 31 inwardly of the link 34 and at the other end is connected at 40 with the gear 24 so as to rock said arm 31 as said gear 24 is rotated by the motor shaft 18 through the train of gears heretofore described.

The motor shaft 18 is connected to any suitable source of power such as an electric motor 41 and as said motor is operated said arm 31 oscillates about its pivoted end 32 to raise and lower the plate 15 and its attached pusher plate 17 for removing the endmost sheet in the pack of sheets in the hopper 3.

45 A delivery chute 42 is secured to the front end of the hopper 3 and is curved downwardly terminating approximately at the front end of the first tank A, so that a sheet removed from the hopper 3 by the pusher plate 17 slides by gravity down said chute 42 towards tank A.

The conveyor mechanism for the several tanks is substantially the same and hence but one conveyor mechanism will be described in detail.

50 The conveyor mechanism for tank A com-

prises a bevel gear 43 mounted on transfer shaft 44 which supports said gear adjacent the tank. Two other gears 43a are mounted on shaft 44, one on each side of the tank. The 5 gears 43a are disposed outwardly of the sides of the tank as may be seen in Figures 4 and 3.

A description of the mechanism at one side of the tank will be sufficient as the mechanism on the other side is duplicated.

- 10 The bevel gear 43 is driven by a small bevel gear 45 keyed to the shaft 30. A transverse shaft 46 is carried in the side frame members of the machine and is disposed a slight distance above the top of the tank A. Small 15 sprockets 47 are carried on this shaft with one near each side of the tank. Another transverse shaft 48 is mounted above the tank A and ahead of the shaft 46. This shaft carries sprockets 49 similar to sprockets 47. 20 Idler sprockets 50 are carried by shaft 51 arranged a slight distance above the sprockets 47, which idlers serve as tighteners for the conveyor chains.

- Endless conveyor chains 52 pass around 25 the sprockets 43a, 47, 48, and are maintained in tight position by the idlers 50. The chains are special ones having attached to the links thereof angle members 53 and 54 on each side thereof to which angle members are attached 30 work piece frames such as shown in Figure 9.

- Figure 9 is a perspective view of a work-piece frame or sheet carrier which is illustrated as one means of receiving a sheet for conveying the same through the plating apparatus of my invention. Said sheet carrier comprises a body 55 skeleton-like in form having a large cut-out 56. The margins of the body 55 are provided with upturned pieces 55a while a hooded portion 57 overlies 35 the upper end of the sheet carrier engaging the upper margins of the side portions 55a thus being spaced from the body 55. The width of the hood 57 is slight compared to its length. The lower end of the sheet carrier is formed with a channel formed by bending back on itself the lower end of the sheet material of which the body 55 is made as at 58. Cut-outs 59 and 60 are provided in the channel at the lower end of the sheet 40 carrier for a purpose to be hereinafter described.

- The sheet carrier has at its upper end and at each side thereof an outwardly extending flat piece 61 welded, riveted or otherwise secured to the body 55 which piece 61 has a 45 cut-out 62 extending upwardly from the lower edge of said piece. The piece 61 is provided with rivet or bolt holes 63 whereby said pieces 61 may be riveted, bolted or otherwise fastened to the angle pieces 53 and 54 50 on the chain 52.

- A sheet carrier is supported transversely of the tank A by having the pieces 61 thereof fastened to the angle pieces 53 and 54 on the 55 chain 52 at each side of the tank so that said

sheet carriers are rigidly secured to the chain and move with the chain as the same is driven by the sprocket 43.

The driving sprocket 43 of the transfer mechanism for tank A is so associated and timed with the main driving shaft 30 that one of the sheet carriers 55 is moved into the horizontal position E of Figure 1 as the sheet is delivered from the supply hopper 3 and slides down the chute 42 entering the sheet carrier 55 with the advancing edge of the sheet moving underneath the hood 57 and the rear edge being received within the channel 58 at the bottom of the sheet carrier.

Continued operation of the main driving shaft 30 will move the next sheet carrier into the position E for reception of the next plate delivered from the supply hopper to the chute 42 by the pusher plate 17. This continues as long as there are any plates in the supply hopper 3 and as long as it is desired of continuing operation of the plating apparatus.

The sheets in the several sheet carriers on the lower run of the chain 52 are thereby moved through the liquid within the tank A. The chain 52 after passing the sprocket 49 moves upwardly into position to have the sheets removed from the sheet carrier.

Adjacent the arc of movement of the sheet carriers 55 in the upward direction as may be observed from Figure 1 and Figure 2 of the drawings is a transverse shaft 64 carrying a pair of spaced fingers 65 spaced so that a finger will enter each of the recesses 59 or 60 in the bottom edge of the frame 55. The shaft 64 may be driven in any desirable manner in timed relation with the driving shaft 30. The fingers 65 are so arranged as to turn in clockwise direction as observed in Figures 1 and 2 and as the sheet carrier 55 moves into the F position the fingers 65 will enter the slots 59 and 60 in the same as observed in Figure 11 and move the sheet backwardly within its sheet carrier. Continued rotation of the shaft 64 moves back the sheet so that the lower edge of the sheet then is freed from the inturned margin 58 of the sheet carrier whereupon said sheet falls as shown in dotted lines in Figure 12 onto an inclined platform 66 which is slotted so that liquid may fall out of the drainboard 67 and be returned to the tank A.

The incline 66 is arranged to then deliver the sheet to a sheet carrier 55 of the next successive conveyor or transfer mechanism where said sheet is delivered into said sheet carrier in exactly the same manner as delivered in the first instance from the chute 42 at the receiving end of the machine.

The conveyor or transfer mechanism for tank B is similar to that described with respect to tank A and operates in the same timed relation so that one of the sheet car-

riers of this conveyor mechanism is in a horizontal position to receive the sheet just removed from the sheet carrier 55 of the first transfer mechanism and moves said sheet through the tank B or washing water tank.

15 The sheet having been moved through the washing water tank in the manner described with reference to tank A is then delivered to the plating tank C for plating.

10 The plating tank C is much longer than tanks A, B, and D so that the sheets may be allowed to remain in said plating tank a sufficient length of time to effect and secure full and complete plating of the sheets.

15 The sheet is then removed from the plating tank C and delivered to the oil tank D whereupon it is given an oil treatment and then removed from said tank D by the conveyor or transfer mechanism for said tank and delivered outwardly of the apparatus.

20 Figure 5 is a top plan view of the plating tank C and shows a plurality of anodes arranged in said tank. The anodes which I prefer to employ are like that shown in Figure 6, which anodes are provided with a hook 68 at one end and an eye 69 at the other end so that a plurality of these may be arranged in series electrically as shown in Figure 5. A plurality of the anodes are arranged flatwise on the bottom of the tank C as shown in Figures 4 and 5 of the drawings and another series are suspended along the inside walls of the tank for increasing the amount of flow of electrical current while any of the sheets are in the plating tank.

25 The anodes are electrically connected by means not shown with a suitable source of electrical energy not shown which source is of course dependent on the kind of plating being done and also the amount of current being supplied to the plating tank. A plating solution of proper kind and mixture is placed in the plating tank C so as to form the electrolyte for making proper deposits on the sheets being plated.

30 A bus bar 70 is arranged along the top edge of each side of the plating tank C being suitably insulated at 71 from its attaching member 72. The bus bar is electrically connected with the source of electrical current to which is also connected the anodes.

35 The recesses 62 in the pieces 61 of all of the sheet carriers 55 receive rollers 73 carried by brackets 74 suitably attached to the end pieces 61. The rollers 73 make electrical circuit connections between the bus bars 71, the end pieces 61, the sheet carriers 55 and the supported sheets in said carriers, the elements just recited constituting the cathode of the 40 electrical circuit through the plating tank.

45 Electric circuit is established through the sheets supported by the sheet carriers 55 as soon as any part of the sheet carriers enters the plating bath in the tank C. Arrangement of the conveyor and transfer mecha-

nism is such as to move the sheets through the plating solution with the electrical current flowing through said solution for a sufficient length of time to properly plate the sheets on both sides and throughout both surfaces of 50 said plates.

The anodes in the tank C are connected in series parallel, that is the anodes on the bottom of the tank as well as the anodes alongside the inner walls of the same.

55 An electrical conductor 75 is supported within the wall of the tank C and near the upper edge thereof from which conductor hang the several anodes arranged against said wall. Furthermore, said conductor is electrically connected with the anodes on the bottom of the tank.

60 It will be observed that the sequence of delivering, receiving and moving sheets to the machine is done automatically once the machine has been put in operation and there is a supply of sheets in the hopper 3.

65 The invention is illustrated and described in connection with an electroplating machine for plating flat sheets. It is, of course, within the scope of this invention to rearrange the machine for plating articles other than flat sheets. In such event necessarily the supply hopper would be different or omitted and the delivery chute 42 of such shape and arrangement as to deliver the other articles to the carriers on the conveyor and transfer mechanism for the several tanks. The frame 55 might easily be removed and suitable carriers for other articles shaped otherwise than 70 flat applied to the chain 52.

75 The sprocket wheel 43a is large so that proper arrangement may be made between the several conveyors, and also that proper speed of the conveyor chains may be obtained.

80 The machine is of course properly insulated so as to prevent short circuits and so as to assure proper flow of current through the plating bath.

85 While I have described more or less precisely the details of construction of my invention, yet I do not wish to be limited thereto as I am aware that changes may be made in the arrangement and proportion of parts and that equivalents may be substituted, all without departing from the spirit and scope of my invention.

90 I claim as my invention:

95 1. Transfer mechanism for conducting flat sheets through a treating tank comprising a pair of chains adjacent the sides of said tank, sprockets for driving and supporting said chains, a plurality of sheet carriers connected to said chains so as to lie transversely of the tank, said sheet carriers arranged to each receive a single sheet, a receptacle for said sheets, means for withdrawing said sheets singly from said receptacle and delivering the same successively to said sheet carriers, means 100 for driving said chains in timed relation with 105

said sheet withdrawing means, and automatic means including a rotating finger for dislodging a sheet from a carrier after the carrier has been moved by said chains out of said 5 treating tank.

2. A conveyor and transfer mechanism for a treating tank comprising a pair of endless chains arranged adjacent the sides of said tank, sheet carriers secured to said chains, 10 every sheet carrier having a recess in the lower side thereof to receive the lower margin of a sheet and maintain the same in the carrier, trip means including a rotating member engageable with a sheet adjacent the discharge end of said tank for dislodging a sheet from said recess to thus cause the sheet to gravitate from said carrier, and means for receiving said sheet as the same falls from said carrier.

20 3. An automatic sheet conveying apparatus for a treating tank comprising means for delivering sheets to said tank, a conveyor for receiving said sheets and moving the same to and through said tank, said conveyor including a pair of endless chains on each side of the tank, a plurality of sheet carriers supported by said chains transversely of the tank, the bottom of every sheet carrier having a channel for receiving a sheet and a hood cooperating with the channel for retaining a sheet in a carrier, tracks along said tank, means carried by said sheet carriers for engaging said tracks, means for driving said chains continuously, and means including a rotating finger adjacent the delivery end of said tank for dislodging sheets from successive sheet carriers.

4. An automatic conveying apparatus for a treating tank comprising two endless chains 40 arranged one on each side of the tank, a plurality of sheet receiving members rigidly secured to said chain, each of said members being constructed to receive a single sheet and support the same in position as said sheet is moved through and from the tank, means for driving said chains and means including a rotating finger adjacent the delivery end of said tank and operating in timed relation with the chain driving means for dislodging 45 sheets from the sheet carrying members as said members are moved from the tank by said chain.

5. An apparatus for treating flat sheets comprising a tank, a conveyor and transfer mechanism for said tank comprising a pair of endless chains arranged adjacent the sides of said tank, sheet carriers secured to said chains, every sheet carrier having a recess in the lower side thereof to receive the lower 55 margin of a sheet, a rotating trip adjacent the discharge end of said tank for dislodging a sheet from said recess to thus cause the same to gravitate from said carrier, means for receiving said sheet as the same falls from said 60 sheet carrier, tracks along said tank, means

carried by said sheet carriers for engaging said tracks as said carriers are moved through the tank, and means for operating said chains and said trip means automatically and in 70 timed relation.

6. A treating apparatus for rigid sheets comprising a plurality of tanks arranged in end-to-end relation, conveyor and transfer mechanisms for every tank, means for delivering single sheets to the conveyor mechanism in the first tank, said means including a sheet supply hopper, means for supporting a pack of sheets in edgewise position in said hopper, a chute leading from the lower end of said hopper toward the receiving end of the first tank, means including a pusher plate engageable against the top edge of a sheet for removing a single sheet from said hopper onto said chute, said conveyor mechanism comprising a pair of chains arranged one on each side of the tank, sheet carrying members supported by said chains and extending transversely of the tank and movable with the chains, the sheet removing mechanism being effective to remove a sheet from said hopper onto the chute for delivery to one of the sheet receiving members on the chain as one of said members is moved into position at the end of said chute, means for driving said chains, and means for actuating said sheet remover, said 80 chain driving means and said sheet withdrawing means being operated automatically and in timed relation, and a rotating finger engageable with a sheet in its receiving means for dislodging said sheet therefrom to discharge the same from said conveyor.

7. An apparatus for treating rigid sheets including a tank, a conveyor mechanism associated with said tank, said mechanism comprising two endless chains arranged one adjacent each side of said tank, sheet receiving members attached to said chains and extending transversely of the tank, means on said members for supporting a sheet along its margin, means for driving said chains continuously and at a constant speed, means for delivering a sheet to a sheet receiving member as said chains are moved, means for removing sheets from said members as said chains lift the sheet receiving members from the treating tank comprising a rotating finger driven in timed relation with the chain driving means for engaging an edge of the sheet in its carrying member and displacing said sheet from said member, and means for receiving a sheet so dislodged from its carrying member for delivering said sheet elsewhere.

8. A conveyor mechanism for rigid sheets, comprising an endless chain, hanger frames secured at intervals on said chain, each of said frames having inturned edges for maintaining a rigid sheet in a frame, means for feeding sheets to said frame, and means including a rotating finger for ejecting the sheets from the frames, all of said means op- 125

erating automatically and in timed relation.

9. Apparatus for transporting rigid sheets through a treating tank comprising a pair of endless chains, hanger frames rigidly secured at intervals to said chains, every hanger frame having inturned edges on one face of the same to provide recesses for receiving the margins of a rigid sheet, the lower edge of every frame having notches therein, means for moving said chains, means for supplying sheets to said hanger frames, and means rotating into the notches of successive frames for engaging the margin of a sheet therein in order to eject the same therefrom, all of said means operating in timed relation.

10 In testimony whereof I have hereunto subscribed by name at Chicago, Cook County, Illinois.

MICHAEL A. MESSLEIN.
